UNITED STATES PATENT OFFICE.

EARL PHILLIPS, OF CLEVELAND, OHIO.

DESIGN FOR A SHOE-SOLE OR SIMILAR ARTICLE.

55,397.

Specification for Design.

Patented June 1, 1920.

Application filed February 3, 1920. Serial No. 355,984. Term of patent 7 years.

To all whom it may concern:

Be it known that I, EARL PHILLIPS, a citizen of the United States, residing at Cleveland, in the county of Cuyahoga and State of Ohio, have invented a new, original, and ornamental Design for a Shoe-Sole or Similar Article, of which the following is

a specification, reference being had to the accompanying drawing, forming part thereof.

The figure is a perspective view of a rubber sole and heel, showing my new design.

I claim the ornamental design for a shoe sole or similar article, as shown.

EARL PHILLIPS.
